UNITED STATES PATENT OFFICE.

ALBERT HORACE DENAULT, OF SAULT STE. MARIE, ONTARIO, CANADA.

INCUBATOR.

Application filed January 4, 1926. Serial No. 79,250.

This invention relates to improvements in incubators, and more particularly to improved means for turning the eggs in incubators and the objects of the invention are to provide a simple and durably constructed incubator provided with means operable from the outside for accurately turning the eggs to a predetermined extent during the period of incubation without touching them and whereby more satisfactory results are obtained.

Further objects are the provision of means of this character that can be readily fitted to an incubator and of which the parts are few and readily assembled.

With the foregoing and other objects in view the invention consists essentially in the combination, with the egg-holding rack of an incubator, of a shaft, slidably operable from the outside of the incubator, extending beneath the rack and provided with an egg-turning member adapted to engage and disengage with the eggs in the rack and means in the shaft, also operable from the outside of the incubator, for operating the turning member.

Referring now to the drawings in which like characters of reference indicate corresponding parts in each figure:

Figure 1 is a side elevation partly in section;

Figure 2 is a longitudinal section;

Figure 3 is a section on line 3—3 of Figure 2;

Figure 4 is a longitudinal section of the shaft carrying the turning member with dotted lines showing its inoperative position in relation to the egg-carrying rack;

Figure 5 is a section on line 5—5 of Figure 4;

Figure 6 is a perspective detail of the turning member;

Figure 7 is a detail of the egg-carrying rack;

Figure 8 is a perspective view of the top side of the screen tray for insertion beneath the rack;

Figure 9 is a perspective view of the underside of the screen tray;

Figure 10 is a longitudinal section through the screen, and

Figure 11 is a plan view of the carrier shaft with its co-operating parts.

Referring now more particularly to the drawings, in which an example of my invention is illustrated, 10 designates the incu-

bator as a whole in the form of a box divided into three compartments 11, 12 and 13 by partitions 14 and 15, the whole being suitably supported above the ground on legs 16. The compartments 11 and 12 in the example illustrated are provided with doors of well known construction opening outwardly at one side. Within the compartment 12 is slidably and detachably arranged 60 the egg-carrying rack 17 adapted to move laterally on supporting guide-ways 18 on the partitions 14 and 15. Beneath the egg-carrying rack and extending longitudinally through the incubator is a carrier shaft 19 mounted on the roller 20 suitably supported on the partition 14 and extending beneath a roller 21 mounted on a spindle 22 between spaced supports or brackets 23 rigidly secured in the compartment 13 on the outer side of the partition 15.

The end 24 of the incubator is also provided with an opening 25 through which the member 19 is designed to travel when operated. This member 19 is provided with a hollow web 26, extending the full length thereof, in which is a carrier plate 27 formed substantially midway of its length with a slantwise cut out 28 to which detachably fits the egg-turning member 29 comprising the flat plate 30 having, on the underside, the forked stem 31 adapted to straddle the carrier plate 27. This turning member is also provided with a roller 32 to engage with the cutout portion 28 of the member 27. For operating the member 27 I provide a screw-threaded rod 33 secured, as at 34 in the end of the member 27. This rod extends through the opening 25 in the end of the incubator and is provided with an operating handle 35 so that when the latter is operated the plate 27 will be moved outwardly causing the lifter roller 32 to travel up the inclined surface 28, automatically raising the member 29 and, on the handle 35 being turned in the opposite direction, the member 29 will automatically assume normal or lowered position as illustrated in Figure 4.

From the foregoing it will be noted that the turning member 29, resting on the plate 27, is automatically raised or lowered by the forward or backward movement of said plate operated through the screw rod 33 and the handle thereon 35. To move the turning member from one row of eggs in the egg rack 17 to the next, it is necessary to move the carrier shaft 19 backwards and

forwards and to accomplish this I provide a toothed rack 36 on the underside thereof designed to mesh with a roller pinion 37 rigidly mounted on a shaft 38 between the 5 supporting members 23, on which the member 19 travels. The shaft 38, as illustrated in Figures 1, 2 and 3, is supported at right angles to the rod 33 and extends through the side of the incubator to carry an operating 10 handle 39.

The turning of the eggs is accomplished as follows: The carrier member or shaft 19 having been operated through the handle 39 to bring the turning member beneath a row 15 of eggs in the egg rack, as illustrated in Figure 2, the handle 35 is operated as previously described to raise the lifter until it contacts with the eggs. The handle 39 is then operated to move the member 19 forward 20 and this forward movement in contact with the eggs causes all the eggs in the first row to make a half turn and so on right across the egg rack 17. The lifter is then, through the handle 35, turned to normal 25 lowered position, as illustrated in Figure 4, and the member 19, which has by this time protruded considerably beyond the incubator, is also returned by operating the handle 35. When the required period of 30 time for incubation has expired the tray 17 may be raised and the screen shelf member 40 inserted therebeneath on the supporting guideways 18. The member 40, as indicated in the extension to Figure 9, is formed in 35 two sections, the screen 40^a being clamped therebetween and secured by suitable means such as rivets or the like.

The egg rack is so constructed with a plurality of suitably spaced and formed bars 40 that the eggs when placed in cross rows therein extend slightly below the open base, this being provided for by the formation of the cross bars which are of lesser width at the extreme base than above it.

45 In Figures 8, 9 and 10 is illustrated the screen shelf or tray previously referred to.

As many changes could be made in the above construction and many apparently 50 widely different embodiments of my invention, within the scope of the claims, con-

structed without departing from the spirit or scope thereof, it is intended that all matter contained in the present specification and accompanying drawings shall be interpreted in an illustrative and not in a limiting sense.

What I claim as my invention is:

1. In an incubator of the character described and in combination, an egg rack, a slidably mounted shaft beneath the rack, a plate movable in said shaft, a slantwise recess in said plate, an egg-turning member movably mounted in said recess and normally retained in lowered position therein, means for operating the slidable plate whereby on the latter being horizontally moved the egg-turning member engages with the slantwise recess to travel upwardly to contact with the eggs. 60

2. In an incubator and in combination 70 with the egg rack, a slidably mounted shaft operable from without the incubator and extending beneath the egg rack, an egg-turning member adjustably mounted in the shaft, a guideway in the shaft, and means, operable 75 from without the shaft, for causing the egg-turning member to travel in said guideway to engage with the eggs in the rack to turn them.

3. In an incubator, a slidable shaft extending beneath the egg rack, a member carried by said shaft adapted to be raised and lowered to engage with the rows of eggs in the rack to turn them and mechanism, operable from without the incubator, for imparting 80 a backward and forward movement to the shaft and an upward and downward movement to said member carried thereby. 85

4. In an incubator of the character described the combination, with an egg rack, 90 of a slidably mounted shaft operable from without the incubator, an egg-turning member carried by said shaft, mechanism operable from without the shaft and means in the shaft for imparting an upward and 95 downward movement to the egg-turning member.

In witness whereof I have hereunto set my hand.

ALBERT HORACE DENAULT.
